Patented Jan. 11, 1916.

UNITED STATES PATENT OFFICE.

JOHN L. LOFTS, OF CLARINDA, IOWA.

WIRE-REEL.

1,167,704.

Specification of Letters Patent.

Patented Jan. 11, 1916.

Application filed March 8, 1915. Serial No. 13,018.

To all whom it may concern:

Be it known that I, JOHN L. LOFTS, a citizen of the United States, residing at Clarinda, in the county of Page, State of Iowa, have invented certain new and useful Improvements in Wire-Reels; and I do hereby declare the following to be a full, clear, and exact description of the invention, such as will enable others skilled in the art to which it appertains to make and use the same.

This invention relates to wire reels and particularly those of the type adapted to be mounted upon a wagon body.

The object of the invention resides in the provision of a wire reel of the type named embodying an improved construction for mounting same upon the body of a wagon and also embodying means for controlling the playing out of the wire as the wagon is moved along the ground whereby the wire may be stretched by the movement of the wagon without the necessity of employing an independent wire stretcher.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a plan view of the rear end of a wagon body having the improved wire reel mounted thereon; Fig. 2, a rear view of what is shown in Fig. 1 with the tail gate removed; Fig. 3, a section on the line 3—3 of Fig. 1 with the reel removed from its supporting shaft; Fig. 4, a section on the line 4—4 of Fig. 1, and Fig. 5, a side view of what is shown in Fig. 1.

Referring to the drawings A indicates generally the body of a wagon which includes side members 10 and 11. Disposed on each side of the body A is the usual wagon standard 12.

The improved reel is shown as comprising a substantially U-shaped bar B including arms 13 and 14 having their free ends directly outwardly as at 15. Secured to the

outwardly directed portions 15 of the bar B are U-shaped brackets 16 disposed in substantially the same plane as said bar and 55 detachably engaged over the sides 10 and 11 respectively of the body A. Also secured to the outwardly directed portions 15 are U-shaped brackets 17 disposed oppositely to the bracket 16 and in a plane at right angles 60 to the plane of the bar B. Seated in the bracket 17 is a shaft 18 which has rotatably mounted on the central portion thereof a brake wheel 19 having studs 20 projecting laterally from each end thereof. Slidably 65 adjustable on the shaft 18 between the brake wheel 19 and each bracket 17 is a collar 21 carrying a set screw 22 and through the medium of which latter said collar is secured against longitudinal movement on the shaft 70 18. Fixed to the bar B is an arm 23 to the free end of which is pivotally connected a brake shoe 24 movable in the plane of the wheel 19 and adapted to be brought into engagement with the periphery of said wheel 75 to resist and retard the rotation thereof. Secured to each end of the shaft 18 in an adjustable manner is a hook 25 adapted to be detachably engaged with the adjacent standard 12. The shaft 18 is adapted to rotatably support a wire reel 26 of the usual construction between the wheel 19 and either collar 21. Such a reel is shown mounted upon the shaft 18 in Fig. 1 and when so mounted the adjacent studs 20 interlock 80 with the frame of the reel whereby the brake wheel 19 and reel 26 rotate in unison and any retarding of the rotation of the wheel 19 through the medium of the brake shoe 24 will effect a corresponding retardation 85 of the reel 26 and through this instrumentality the wire can be stretched as the wagon moves along the ground without the use of an independent wire stretcher.

What is claimed is:—

In a device of the class described the combination of a substantially U-shaped bar having the free ends of its arm directed outwardly, U-shaped brackets secured to the free ends of said arms and adapted for detachable engagement with the sides of a wagon body, additional U-shaped brackets secured to the free ends of the bar, a shaft engaged in the last named bracket, hooks

connected with the ends of said shaft and detachably engageable with a relatively fixed part, a brake wheel rotatably mounted on the shaft, a brake shoe pivotally connected with the bar and engageable with the periphery of the wheel to retard the rotation of the latter, and lateral studs on said wheel adapted to interlock with a wire reel

rotatably mounted on the shaft to effect unitary rotation of the wheel and reel. 10

In testimony whereof, I affix my signature, in the presence of two witnesses.

JOHN L. LOFTS.
